(57) CLAIM

The ornamental design for a billiards showroom kiosk, as shown and described.

DESCRIPTION

FIG. 1 is a perspective view of a billiards showroom kiosk, showing my new design;

FIG. 2 is a front elevational view;

FIG. 3 is a rear elevational view;

FIG. 4 is a top plan view; and,

FIG. 5 is a left-hand side elevational view, wherein the right-hand side elevational view is substantially identical.
